(57) **CLAIM**

The ornamental design for a nasal elevator, as shown and described.

DESCRIPTION

FIG. 1 is a perspective view of a first embodiment of a nasal elevator.

FIG. 2 is attachment end view of the nasal elevator shown in FIG. 1.

FIG. 3 is a hook end view of the nasal elevator shown in FIG. 1.

FIG. 4 is a first side view of the nasal elevator shown in FIG. 1.

FIG. 5 is a view of the other side of the nasal elevator shown in FIG. 1.

FIG. 6 is a bottom view of the nasal elevator shown in FIG. 1.

FIG. 7 is a top view of the nasal elevator shown in FIG. 1.

FIG. 8 is another perspective view of the nasal elevator of FIG. 1 with alternative environmental structure shown in broken lines.

FIG. 9 is an enlarged version of FIG. 8 with part of the environmental structure shown in FIG. 8 omitted.

FIG. 10 is an attachment end view of the nasal elevator shown in FIG. 9.

FIG. 11 is a hook end view of the nasal elevator shown in FIG. 9.

FIG. 12 is a first side view of the nasal elevator shown in FIG. 9.

FIG. 13 is a view of the other side of the nasal elevator shown in FIG. 9.

FIG. 14 is a bottom view of the nasal elevator shown in FIG. 9; and,

FIG. 15 is a top view of the nasal elevator shown in FIG. 9. Portions of the nasal elevator shown in broken lines in the figures form no part of the claimed design.
